UNITED STATES PATENT OFFICE

ALFRED LA FRANCE, OF CENTRAL FALLS, RHODE ISLAND

ROTATABLLE DRAWING BOARD AND ATTACHED STRAIGHTEDGE

Application filed October 23, 1929. Serial No. 401,760.

This invention relates to a drafting device, the general object of the invention being to provide a device which will take the place of a number of the instruments now used, so that it is not necessary to pick up or lay aside such instruments, and it eliminates the use of triangles.

A further object of the invention is to provide means whereby all lines are drawn in a horizontal position and a line can be drawn at any angle and the full width of the board.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is a plan view of the device.

Figure 2 is an edge view.

Figure 3 is a similar view, but taken at right angles to Figure 2.

Figure 4 is a section on line 4-4 of Figure 1.

Figure 5 is a section on line 5-5 of Figure 1.

Figure 6 is a section on line 6-6 of Figure 1.

Figure 7 is a plan view, partly in section, showing the means for controlling the movement of the turntable.

Figure 8 is a top plan view with the square strip removed and showing the means for adjusting the square over the board.

Figure 9 is a section on line 9-9 of Figure 8.

Figure 10 is a section on line 10-10 of Figure 9.

In these views, the numeral 1 indicates the supporting member to which the turntable 2 is pivoted at its center, as shown at 3, the upper part of the supporting member being recessed to receive the table so that the table is flush with the upper surface of said member. A board 4 is removably placed on the

table and is caused to turn therewith by means of the projection 5 on the table engaging a notch 6 in the board. The board is of less diameter than the table so that the periphery of the table is exposed and a portion of the periphery of the table is formed with the teeth 7 which form graduations on the table and these graduations are divided into tenths by the numerals and lines 8. A bar 9 is arranged in a space in the supporting member and has an arm 10 intermediate its ends which carries a pin 11 projecting through a hole 12 in the supporting member and adapted to engage the teeth 7, the pin being normally held in engagement with the teeth by the spring 13 which connects the central part of the bar with a part of the supporting member. One end of the bar 9 is pivoted to an arm 14 arranged in an opening 15 in the supporting member, and this arm is connected by a screw 16 with an arm 17 which operates over a plate 18 on the supporting member, said plate having a hole 19 therein through which a part 14' of the arm 14 extends, so that the two arms are pivotally supported by the plate, and the movement of the outer arm 17 will be communicated to the arm 14. The plate carries a raised portion 20 having a vernier on its upper surface and a spring plunger 21 is carried by the arm 17 and frictionally engages the inner wall of the enlargement 20 so that this plunger acts to hold the arm 17 in adjusted position. The other end of the bar 9 has a slot therein for receiving a headed pin 22 depending from an arm 23 having a bearing part 24 passing through a hole in a plate 25 carried by the supporting member and an arm 26 is fastened to the bearing part and operates over the plate 25 so that by moving this arm 26, the arm 23 is moved and this movement of the arm 23 will swing the bar 9 outwardly against the action of its spring and thus move the pin 11 out of engagement with the toothed portion of the table so that the table is free to move. The arm 26 carries a spring plunger 27 which is adapted to engage a hole 28 in the plate 25 when the arm is moved to a position to swing the bar 9 outwardly, thus 100

holding the bar in this position against the action of its spring 13. The arms 17 and 14 act to move the bar 9 longitudinally and thus cause the pin 11 to move the table a 5 certain distance on its pivot 3 and this distance can be accurately gauged by the vernier on the enlargement 20.

From the foregoing it will be seen that the table can be accurately moved by moving 10 the arm 17 to certain distances and by moving the bar 9 by the arm 26, the table will be freed of the pin 11 so that the table can be turned freely to any desired position.

A guide bar 29 is supported at one edge 15 of the board by the projections 30, this bar having a reduced lower part which is formed with the rack teeth 31 on its inner edge and a channel shaped member 32 is slidably arranged on the bar and is formed with a casing 33 at its center. A graduated elongated plate 34 has one end fastened to the casing by the screws 35 and this plate 34 and the member 32 forms a T square. That end of the plate 34 which is connected with the casing forms a cover for the casing. A pressure bar 36 is arranged in the casing and carries a roller 37 at its inner end for engaging the inner edge of the bar 29 and said bar 36 carries a spring 38 which is forced 20 against a part of the casing by a thumb screw 39 threaded in the outer end of the member 36. Thus this bar and its parts act to frictionally connect the casing with the bar 29, and the frictional engagement of the 25 roller with the bar 29 can be controlled by adjustment of the spring 38 by the screw 39. A lever 40 is pivoted in the casing and has a projection 41 thereon engaging a notch in the member 36, with one end of the lever 30 projecting outwardly from the casing. Thus by pressing upon the outer end of this lever and against a handle 42 connected with the casing, the bar 36 is moved inwardly so as to move the roller 37 away 40 from the bar 29 and thus permit the member 32 to have free movement on the bar 29.

A lever 43 is pivoted in the casing between the lever 40 and the handle 42 and the inner end of this lever 43 has a dog 44 pivoted 50 thereto, with the dog engaging the rack teeth 31. The dog 44 is frictionally connected with the lever 43, as shown at 45, and a spring 46 normally holds the lever with its inner end against a wall of the casing and 55 the dog retracted.

A combined lever and pointer 47 is frictionally pivoted to a part of the casing and has its pointed end passing through the casing and this pointed end operates over a 60 scale 48 on the member 32. The inner part of the lever carries a depending projection 49 which extends into the path of the pawl and acts to control the movement of the pawl by the lever 43. When the lever 47 is on the 65 graduation 1 of the scale 48, the pawl has

but a limited movement so that when the pawl is operated by the lever 43, the T square is moved but one step on the bar 31, but when the lever 47 has its pointed end opposite the graduation 4, the T square is moved 70 four steps or over four teeth 31 every time the pawl is moved by the lever 43.

Thus it will be seen that by pressing with the thumb and a finger of one hand upon the handle 42 and the lever 40, the friction bar 75 36 is moved to position the roller 37 out of contact with the guide bar 29 so that the T square can be adjusted to any position over the board on the turntable and by placing the thumb and finger on the handle 42 and the 80 lever 43 and applying pressure upon the lever 43, the T square is moved by the dog a certain distance, this distance being controlled by the positioning of the lever 47 on the scale 48. Thus it will be seen that I have provided a device which will take the place of a 85 number of instruments now used in drafting, with all the controls at the fingertips ready to operate without having to pick up or lay aside different instruments. The T square 90 will remain in a set position when the board is inclined and it can be adjusted to any desired position on the board and the board can be turned to draw lines on the sheet thereon, through means of the T square, at any angle 95 and the full width of the board. The board and the turntable can revolve in either direction and it can be locked at every degree and can be shifted in fractions of a degree while in locked position. The lock can be moved 100 to inoperative position and held there so that the board can be turned at will. The member 32 has slight tilting movement on the bar 29 so that by slight pressure upon the handle, the square can be raised above the board so 105 that it will pass over thumb tacks or the like.

While the drawings show the board on the turntable of circular shape, it will, of course, be understood that any shape of board can be 110 placed thereon.

It is thought from the foregoing description that the advantages and novel features of the invention will be readily apparent.

It is to be understood that changes may be 115 made in the construction and in the combination and arrangement of the several parts, provided that such changes fall within the scope of the appended claims.

What I claim is:—

1. A drafting instrument comprising a supporting member, a turntable thereon, locking means for the same, means for adjusting the table when in locked position, a guide bar on the supporting means, a T-square slidably 125 arranged on the bar, adjustable means for frictionally holding the square against movement, a lever for moving the friction means into inoperative position, said guide bar having rack teeth thereon, a pawl carried by a 130

part of the T square and engaging the teeth, a lever for operating the pawl, a second lever for controlling the amount of movement of the pawl by the lever.

- 5 2. A drafting instrument comprising a supporting member, a turntable thereon, locking means for the same, means for adjusting the table when in locked position, a guide bar on the supporting means, a T square slidably arranged on the bar, adjustable means for frictionally holding the square against movement, a lever for moving the friction means into inoperative position, said guide bar having rack teeth thereon, a pawl carried by a
- 10 part of the T square and engaging the teeth, a lever for operating the pawl, a second lever for controlling the amount of movement of the pawl by the lever, a scale for facilitating the adjustment of the control lever and means
- 15 20 whereby the square can be tilted on the guide bar to raise the same above the table.

In testimony whereof I affix my signature.
ALFRED LA FRANCE.
